UNITED STATES PATENT OFFICE

2,609,776

LOADING AND UNLOADING APPARATUS

Henry Sahlin, Birmingham, Mich.

Application February 11, 1948, Serial No. 7,643

5 Claims. (Cl. 113—50)

1

This invention relates to material handling apparatus and in particular to an apparatus adapted automatically to unload metal stampings or pressed metal panels from a press or machine, or conversely to load or feed metal blanks or sheets into the press or machine preparatory to the operations of the latter.

An object of the invention is to provide an apparatus adapted to be mounted on or alongside a press or machine and having a swinging pendant arm provided at its lower end with means for gripping or otherwise supporting a sheet metal blank or stamping, the apparatus embodying means for swinging the pendant arm relatively to the press and independently of the movable member or ram of the press or the movement thereof.

A further object of the invention is to provide a loading or unloading apparatus of the foregoing character in which the actuating means for the pendant arm imparts thereto a vertical movement at the time the blank or stamping lies within the press or machine and thereafter a bodily swinging machine toward or away from the press. Such movements of the pendant arm are particularly advantageous in unloading comparatively deep drawn stampings from a press since the pendant arm, before it is swung away from the press, will first lift the stamping clear of any obstruction in the lower die.

Still a further object of the invention is to provide an apparatus of the foregoing character having means, preferably fluid actuated, connected to the upper end of the pendant arm for shifting the same vertically, means such as cam means being provided for imparting a predetermined swinging motion to the arm during its vertical travel. As a result of the improved construction and mode of operation a compound motion, i. e. simultaneous vertical and swinging, is imparted to the pendant arm thereby achieving important advantages. For example, the pendant arm may be shortened; it may be given a greater angular motion; and its lower end will be swung outwardly a less distance from the press than heretofore, thus enabling the apparatus to be used effectively where the space between rows of presses in a plant is restricted.

Other objects of this invention will appear in the following description and appended claims, reference being had to the accompanying drawings formed a part of this specification wherein like reference characters designate corresponding parts in the several views.

Fig. 1 is a fragmentary front elevation of a press equipped with an apparatus embodying the present invention.

Fig. 2 is an enlarged fragmentary vertical section taken substantially through lines 2—2

2

of Fig. 1 looking in the direction of the arrows.

Fig. 3 is a view in part similar to Fig. 2 but illustrating the position of certain of the operating mechanism when the stamping or panel has been fully withdrawn from the press.

Fig. 4 is an enlarged section taken substantially through lines 4—4 of Fig. 2 looking in the direction of the arrows.

Fig. 5 is an enlarged section taken substantially through lines 5—5 of Fig. 2 looking in the direction of the arrows.

Fig. 6 is an enlarged section taken substantially through lines 6—6 of Fig. 2 looking in the direction of the arrows.

Fig. 7 is an enlarged section taken substantially through lines 7—7 of Fig. 2 looking in the direction of the arrows.

Fig. 8 is an enlarged fragmentary sectional view illustrating the parts enclosed within the circle designated 8 in Fig. 2.

Fig. 9 is an enlarged fragmentary sectional view illustrating the clamping jaws and certain of the operating mechanism therefor.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the invention as applied to an apparatus operable for the purpose of unloading or withdrawing stampings, pressed metal panels or the like from a press. It will be understood that, with suitable changes not affecting the broad concept of the invention, an apparatus embodying the invention may be utilized for loading or feeding blanks into a press. Moreover, although clamping or gripping jaws are employed in the illustrated apparatus for grasping the metal stamping or work during its withdrawal from the press, it will be understood that other means for supporting the work during the handling thereof may be employed without departing from the invention in its broader aspects.

Referring particularly to Fig. 1, there is illustrated generally at A a press of any well known or conventional type, such as a stamping press, having a bed or base 10 carrying a lower die 11. The press is also equipped with the usual vertically reciprocable ram 12 carrying a punch or die 13 cooperable with the bottom die 11 for the purpose of stamping out or drawing a panel P from a sheet metal blank.

Rigidly fixed in any suitable manner to the upper part of the frame of the press is an upper

outwardly extending supporting bracket 14 apertured to receive the upper end of a fixed vertical guide shaft 15 which is rigidly secured to the bracket. The apparatus is also provided with a lower outwardly projecting bracket 16 which is fixed in any suitable manner to the frame of the press at a point spaced below the bracket 14. The lower end 15a of the guide shaft 15 is reduced and fitted within an aperture in the bracket 16 and rigidly secured thereto.

A cam block 17 is supported from the upper bracket 14 at a point immediately below the same, and in the present instance this cam block is preferably supported for vertical adjustment relatively to the bracket 14 through the medium of adjusting devices such as the adjusting bolts 18 and 19 and adjusting nuts threaded thereon, as illustrated in Figs. 2 and 3. A pair of similar depending cam plates 20 embrace at their upper ends opposite sides of the cam block 17 and are rigidly secured thereby by bolts 21. The cam plates 20 are thus spaced apart and have their inner edges suitably contoured to provide curved cam surfaces or faces 22 preferably terminating at their lower ends in parallel vertical substantially rectilinear faces 23. A pair of laterally spaced cam rollers 24, see Fig. 5, have rolling engagement with the faces or edges 23, 22 of the depending cam plates 20. These rollers have suitable journal mountings, indicated in general at 25, upon the upper ends of a pair of spaced plates or members 26, the rollers being disposed at the inner sides of these members. The plates or members 26 form the upper portion of a swinging pendant arm generally indicated by the reference character B. As illustrated particularly in Fig. 5, the members 26 of the pendant arm B straddle or embrace opposite sides of a slide 27 which has an inwardly projecting boss 27a. Journalled within a transverse bore 27b in this boss is a horizontal shaft 28 to which the arm members 26 are bolted at 29. From this construction it will be seen that the pendant arm B may be swung in a vertical plane outwardly and inwardly with respect to the press about the axis of the shaft or pivot 28 which is rotatably mounted within the boss 27a of the slide 27.

The slide 27 has a vertical bore 30, see Fig. 5, through which the shaft 15 extends and upon which the slide is guided for vertical movement. The slide 27 has an outwardly extending boss 27c, see Fig. 8, provided with a vertical tapped hole into which is threaded the lower end of a lifting rod 31, the rod being adjustably secured to the boss 27c by means of adjusting nuts 32 and 33. The upper end of the lifting rod 31 is adjustably connected at 34 (Fig. 2) to the lower end of a piston rod 35 which carries at its upper end a piston reciprocable vertically within a fluid cylinder, such as an air cylinder 36, this cylinder being mounted upon a bracket 37 secured to the top of the supporting bracket 14. The piston rod 35 projects freely through a vertical bore 38 in the cam block 17 and an aligned bore 39 in the bracket 14, thus permitting the piston rod to be reciprocated vertically thereby shifting the slide 27 up and down through the medium of the lifting rod 31.

The lower ends of the plates or members 26, forming the upper portion of the pendant arm B, are rigidly connected together through the medium of a stringer or cross bar 40 apertured to receive a tubular arm member 41 which is rigidly secured thereto as by welding. Telescopied into the tube 41 so as to be adjustable therein is a

second depending tube 42, it being noted that the tubular members 41 and 42 together form the lower part of the pendant arm B. A split clamp 43 embraces the lower end of the tube 41 and is rigidly secured thereto by means of a bolt 44, see Fig. 6. Threaded into a tapped hole in the clamp 43 is an adjusting bolt 45 which has a threaded connection at its lower end with a bracket 46 secured to the tube 42. By means of the adjusting bolt 45 and suitable adjusting nuts it will be seen that the tube 42 may be adjusted endwise relatively to the tube 41 thereby varying the vertical position of the clamping jaws, later described, carried at the lower end of the pendant arm.

Referring to Figs. 2 and 7, the lower end of the tubular member 42 is secured within an aperture in a bracket plate 47 which in turn is bolted at 48 to a guide plate or member 49. Slidably in ways 50 on the guide member 49 and interlocked therewith is a clamping slide 51 having an upper forwardly extending fixed jaw member 52. The slide is bifurcated to receive a lower swinging jaw member 53 which is pivoted to the slide at 54 so as to swing toward and from the fixed jaw member 52. Mounted beneath the guide member 49 is a fluid cylinder, such as an air cylinder 55, having a reciprocable piston rod 56 connected at one end to a piston within the cylinder 55 and at its opposite end to the clamping slide 51. Operation of the air cylinder mechanism will shift the clamping slide 51 inwardly and outwardly upon the guide member 49. The pivoted jaw member 53 has a vertically extending arm 53a adapted to engage an abutment 57, when the slide is shifted inwardly, and thereby close the clamping jaws so as to grip the work. Upon outward movement of the slide 51 the arm 53a will engage a rear abutment 58 and thereby open the jaws, the opening movement of jaw 53 being limited by means of a stop pin 59.

Mounted upon a platform 43a carried by the clamping member or bracket 43 is a magnet air valve 60 of any conventional type. Air under pressure from a suitable source of supply is introduced into the air valve 60 through a main inlet 61. An air line 62 leads from the valve to the outer end of the cylinder 55 at one side of the piston therein and a second air line 63 leads from the air valve 60 to the cylinder 55 at the opposite side of the piston. Thus, when air is introduced into the cylinder 55 through air line 62 the clamping slide 51 will be shifted inwardly toward the press, as shown in dotted lines in Fig. 2, air being exhausted at this time through line 63. Conversely, when air under pressure is introduced into the cylinder 55 through line 63 the slide 51 will be withdrawn to the full line position shown in Fig. 2, air at this time being exhausted from the cylinder through line 62.

In the present embodiment the magnet air control valve 60 is utilized to shift the piston within the upper cylinder 36, this being accomplished by means of a conduit or flexible air line 64 communicating with line 62 and leading to the cylinder 36. Energization of the magnet air valve 60 is accomplished through the medium of a suitable limit switch on the press which is actuated by a moving part of the machine in timed relation to the operation of the press at every cycle thereof. For example, a rotary cam type limit switch of conventional kind, generally indicated at 65, may be mounted on a bracket 65a at one side of the press. This switch includes a contact engaged by one of the cams on a cam shaft 66 in the

switch box which carries at its outer end a sprocket driven by a sprocket chain 67 which in turn is driven by a sprocket on the main drive shaft 68 of the press. When a momentary contact is made in the limit switch box 65 at a predetermined time during every cycle of operation of the press, the magnet air valve 60 will be energized through a control relay which holds the circuit closed and thereby maintains the magnet air valve energized during a predetermined period of operation of the pendant arm B. The circuit through the magnet air valve is interrupted and the valve deenergized through the medium of a second limit switch of conventional kind generally indicated at 69, see Fig. 2. This upper limit switch is controlled by a swinging spring pressed arm 70 carrying at its lower end a roller 71 engaged by a pin or plunger 72 carrying at its outer end a contact cam 72a. The cam 72a projects into the path of a cam roller 73, see Figs. 2, 5 and 8, journaled on a bracket 74. This bracket is adjustably mounted on the outer face of the boss 27c through the medium of an adjusting screw 75 extending through a vertical slot 76 in the bracket 74. By loosening the screw the bracket 74 may be adjusted vertically thereby varying the position of the cam roller 73. When the slide 27 has travelled upwardly a predetermined distance the cam roller 73 will engage the cam 72a on the pin 72, thereby swinging the arm 70 and actuating the upper limit switch 69. By adjusting the cam roller 73 vertically the time of its engagement with the cam 72a may be varied, thus varying the upper limit of travel of the slide 27 and, consequently, varying the outward limit of swinging movement of the pendant arm B.

The main limit switch 65 is set so that the press will open to a predetermined extent before contact is made in the switch box. For example, after the ram 12 has on its upward stroke moved punch 13 a given distance, such as six inches, away from the lower die 11 contact may be made at the limit switch 65. At this time the pendant arm B and gripping jaws 52, 53 will occupy their full line positions shown in Fig. 2. When the press opens the stamping P is usually elevated from the lower die by conventional knock out pins, thus positioning the edge of the panel in operative relation to the gripping jaws. Hence, when contact is made at the limit switch 65 causing the magnet valve 60 to be energized, air under pressure will be caused to flow through lines 62 and 64 resulting in forcing the clamping slide 51 inwardly into position between the separated dies 11 and 13 so as to grip the edge of the stamping P upon closing of the jaws. At this time air under pressure flowing through line 64 into the upper air valve 36 will shift the piston rod 35 upwardly, thereby causing the slide 27 to travel upwardly on the guide shaft 15. Due to the inertia of the pendant arm B there will be a sufficient interval between the operation of the jaws to grip the work and the commencement of the upward travel of the slide 27 to permit the jaws to take hold of the panel before vertical movement of the pendant arm is initiated.

During initial upward travel of the slide 27 the cam rollers 24 will travel along the surfaces 23, thus imparting a straight-line upward translatory motion to the pendant arm. The extent of this vertical movement of the pendant arm before it starts to swing outwardly may be varied, if desired, by varying the length of the surfaces 23 and this is particularly important where deep drawn stampings are to be withdrawn from the

press, this initial vertical motion enabling the stamping to be lifted upwardly a sufficient distance to clear any obstruction in the lower die. During continued upward movement of the slide 27 the cam rollers 24 will travel over the inwardly extending curved cam surfaces 22, thereby swinging the pendant arm B outwardly about the transverse horizontal axis of the pivot or shaft 28. When the pendant arm B reaches the outward limit of its swinging motion, as shown in Fig. 3, the cam roller 73 engages the cam 72a on the pin 72, thereby actuating the upper limit switch 69 and breaking the circuit through the magnet air valve 60, resulting in deenergizing this valve and cutting off the flow of air under pressure through the lines 62 and 64 while introducing air under pressure through the line 63. This operation will result in shifting the clamping slide 51 outwardly and causing the jaws 52, 53 to open and release the panel P. At the same time air will exhaust from the upper cylinder 36 through line 64, thereby enabling the slide 27 to descend on guide shaft 15 through gravity. Due to the slight delay in the commencement of the descent of the slide 27 the jaws will release the panel just before the slide starts to descend and the pendant arm starts to swing inwardly through engagement of the cam rollers 24 with the cam faces 22. The pendant arm, as it reaches the lower end of its stroke, will engage an adjustable stop 77 which positions the pendant arm, as shown in full lines in Fig. 2, for a succeeding operation. By virtue of the adjusting screw 45 the vertical position of the clamping jaws may be adjusted so that they will line up correctly with the stamping to be grasped and withdrawn from the press.

By adjusting the cam roller 73 vertically the outward travel of the pendant arm B may be varied so as either to cause the clamping jaws, when open, to drop the panel P rightside up on a suitable support, such as conveyor 78, or to cause the panel to turn over and drop on the conveyor upside down. When the apparatus is not in use provision may be made for holding the pendant arm B at the extreme upward limit of its outward swinging travel. This is accomplished in the present instance by providing an annular groove 79 on the shaft 15 which is cleared by the slide 27 at its upper limit of travel, as shown in Fig. 3. A C-clamp or other split clamping ring (not shown) may be fastened in the groove 79 to form an abutment engaging the lower edge of the slide 27 and preventing the slide from shifting downwardly by gravity.

I claim:

1. In a material handling apparatus for work adapted to be operated on in a press or machine having relatively vertically movable members, comprising supporting means adapted to be mounted at a side of the machine, a slide, guide means carried by said supporting means for guiding the slide in a vertical direction, a swinging arm depending from said slide and pivotally connected thereto for swinging motion toward and from the machine, work gripping means carried by the lower end of the arm, fluid operated means on said supporting means and connected to said slide for shifting the slide in a vertical direction, cooperating cam means on said arm and supporting means for swinging the arm, fluid operated means for operating said work gripping means, electrically controlled means for actuating both of said fluid operated means, a limit switch actuated in timed relation to the operation of the machine for actuating said electrically

controlled means to operate the work gripping means and also for causing said first named fluid operated means to shift the slide upwardly, and a limit switch controlled by said slide for actuating said electrically controlled means to cause release of said gripping means and permit downward travel of the slide.

2. In a material handling apparatus for work adapted to be operated on in a press or machine having relatively vertically movable members, comprising supporting means adapted to be mounted at a side of the machine, a slide separate from said members, guide means carried by said supporting means for guiding the slide in a vertical direction, a swinging arm depending from said slide and pivotally connected thereto for swinging motion toward and from the machine, work gripping means carried by the lower end of the arm, fluid operated means on said supporting means and connected to said slide for shifting the slide in a vertical direction, cooperating cam means on said arm and supporting means for swinging the arm, fluid operated means for operating said work gripping means, control means for controlling the actuation of both of said fluid operated means, means actuated in timed relation to the operation of the machine for actuating said control means to operate the work gripping means and also for causing said first named fluid operated means to shift the slide in a vertical direction, and means controlled by the slide for actuating said control means to cause release of said gripping means and cessation of the vertical travel of the slide in one direction.

3. A material handling apparatus for a press or machine having relatively movable members, comprising supporting means adapted to be mounted in position adjacent said machine, said supporting means comprising spaced upper and lower support members, a stationary vertical guide extending between and secured to said support members, a slide separate from said relatively movable members and mounted for vertical travel on said guide between said support members, a swinging pendant arm pivotally connected to the slide for swinging motion toward and from the machine, work engaging means for loading or unloading the work and carried by the lower end of the arm, fluid operated means on said supporting means and connected to said slide for shifting the slide in a vertical direction, cooperating cam means on said arm and supporting means for swinging the arm, fluid operated means for operating said work engaging means, control means for controlling the actuation of both of said fluid operated means, means actuated in timed relation to the operation of the machine for actuating said control means to operate the work engaging means and also for causing said first named fluid operated means to shift the slide in a vertical direction, and means controlled by the slide for actuating said control means to cause release of said engaging means and cessation of the vertical travel of the slide in one direction.

4. A material handling apparatus for a press or machine having relatively movable members, comprising supporting means adapted to be mounted in position adjacent the machine, guide means carried by said supporting means, slide means separate from said members mounted for reciprocal travel along said guide means, swingable work handling arm means mounted on said slide means for movement toward and from

the machine, cam means on said supporting means for swinging said arm means, work engaging means for loading or unloading the work and mounted adjacent the outer end of said arm means, fluid operated means connected to said slide means for shifting the same in one direction, fluid operated means for operating said work engaging means, control means for controlling the operation of both of said fluid operated means, a common fluid conduit for both of said fluid operated means leading from said control means, means actuated in timed relation to the operation of the machine for actuating said control means to open said fluid conduit to a fluid source and cause fluid to be conveyed simultaneously to both of said fluid operated means thereby to cause said first named fluid operated means to shift the slide means and also to cause said second named fluid operated means to operate said work engaging means, and means on said supporting means arranged in the path of said slide means and controlled by said slide means for actuating said control means to provide for release of said work engaging means and cessation of the travel of said slide means in one direction.

5. A material handling apparatus for a press or machine having relatively movable members, comprising supporting means adapted to be mounted in position adjacent the machine, guide means carried by said supporting means, slide means separate from said members mounted for reciprocable travel along said guide means, swingable work handling arm means mounted on said slide means for movement toward and from the machine, cam means on said supporting means for swinging said arm means, work engaging means for loading or unloading the work and mounted adjacent the outer end of said arm means, fluid operated means connected to said slide means for shifting the same in one direction, fluid operated means for operating said work engaging means, electrically controlled valve means for controlling the operation of both of said fluid operated means, a common fluid conduit for both of said fluid operated means leading from said valve means and adapted to be opened or closed by said valve means, means actuated in timed relation to the operation of the machine for actuating said valve means to open said fluid conduit to a fluid source and cause fluid to be conveyed simultaneously to both of said fluid operated means thereby to cause said second named fluid operated means to operate said work engaging means and sequentially to cause said first named fluid operated means to shift the slide means, and a limit switch on said supporting means arranged in the path of said slide means and controlled by said slide means for closing said valve means to provide for release of said work engaging means and cessation of the travel of said slide means in one direction.
